Primary Examiner — Kelley A Donnelly

(57) **CLAIM**

The ornamental design for a storage shelving unit, as shown
and described.

DESCRIPTION

FIG. 1 is a top perspective view of the storage shelving unit
showing a first embodiment of our new and ornamental
design;

FIG. 2 is a front elevation view thereof;

FIG. 3 is a back elevation view thereof;

FIG. 4 is a side elevation view thereof;

FIG. 5 is an alternate side elevation view thereof;

FIG. 6 is a top plan view thereof;

FIG. 7 is a top perspective view of the storage shelving unit
showing a second embodiment of our new and ornamental
design;

FIG. 8 is a front elevation view thereof;

FIG. 9 is a back elevation view thereof;

FIG. 10 is a side elevation view thereof;

FIG. 11 is an alternate side elevation view thereof; and,

FIG. 12 is a top plan view thereof.

The portions of the storage shelving unit shown in broken
lines in the figures attached hereto form no part of the
claimed design.

1 Claim, 10 Drawing Sheets
